C. FORTH

HEATER MANIFOLD

Filed Sept. 15, 1924

UNITED STATES PATENT OFFICE.

CHARLES FORTH, OF DETROIT, MICHIGAN, ASSIGNOR, BY MESNE ASSIGNMENTS, TO NEW ERA SPRING & SPECIALTY CO., OF GRAND RAPIDS, MICHIGAN, A CORPORATION OF MICHIGAN.

HEATER MANIFOLD.

Application filed September 15, 1924. Serial No. 737,676.

This invention relates to a manifold for an exhaust gas heater and is more particularly adapted for use in the better quality of automobiles, where it is desired to have a plurality of heaters.

I have here shown a manifold which distributes the exhaust gases to a pair of heaters, but obviously more outlets could be added if desired. In exhaust gas heaters it is 10 the practice to tap the exhaust conduit as close to the engine as possible and by so doing one is very liable to transmit a good share of the noises resulting from the explosions in the internal combustion engine to 15 the heaters, therefore making them audible to the occupants of the car. This is quite objectionable, especially so in the better quality cars.

The object of this manifold construction is 20 to distribute the exhaust gas equally to the heaters and in addition to so turn the stream of gas that the impulses are broken up, thereby muffling the noise without taking away and appreciable amount of heat units 25 from the exhaust gases.

In the drawings:

Fig. 1 is an elevation of my manifold construction secured to a pair of exhaust gas heaters.

Fig. 2 is a horizontal section taken on the line 2-2 of Fig. 1, showing my manifold in plan.

Fig. 3 is a horizontal sectional view 35 through the manifold, taken on the line 3-3 of Fig. 1.

Fig. 4 is a vertical sectional view through a portion of the manifold, taken on the line 4-4 of Fig. 2.

In the better grade cars, it is a decided improvement to provide a couple of heaters which may be both located in the rear part of the car or to provide one or more heaters in both compartments of the automobile. a and a' designate heaters which are secured to the floor b of the automobile. These heaters are provided with inlets c and c', and the outlets d and d'.

My invention relates to the manifold which is placed in communication with the intakes c and c' of the heaters. This manifold construction comprises a hollow casting e provided with the intake port f, to which is secured the conduit g, which is placed in communication with the exhaust

line so as to allow the exhaust gas from the engine to pass therein. This manifold is a special casting and is substantially circular in plan, though obviously the general configuration of the manifold is of no moment. This manifold is preferably flattened, thereby bringing the top and bottom walls of the casting fairly close together in comparison to the width or diameter of the manifold. This casting is provided with any desired number of outlet openings, depending upon the number of heaters which are to be attached thereto.

In the drawings I have shown two outlets, though more could be added, depending upon the capacity of the engine. These outlet ports are arranged by providing a pair of holes x in the manifold casting, said holes being directly opposite to each other, one at the top and one in the bottom of the casting. Fitted through these holes is a nipple h, which is internally threaded at one end as at i, to receive a union j for placing the manifold in communication with the intakes c and c' of the heaters. The opposite end of the nipple is externally threaded as k. An enlarged flange m is carried by this nipple, which is of larger diameter than the holes x and adapted to abut against one side of the casting. The intermediate portion of the nipple, which is of tubular construction, is provided with a plurality of ports n which are so located as to register with the interior of the manifold. A nut o is screwed onto the exterior threads of the nipple and when drawn down tightly will tightly secure the nipple to the manifold casting. In the operation of the heaters the exhaust gas is injected into the interior of the manifold through the inlet port f and then passes through the ports n into the interior of the nipple, from where it is led into the exhaust heater for the purpose specified.

Pillars p are cast integral with the manifold for the purpose of reinforcing the same and preventing the same from collapsing.

I claim:

1. A manifold for connecting a plurality of exhaust gas heaters to the exhaust line of an internal combustion engine, having in combination, a flat circular manifold casting provided in the periphery with an intake in connection with the exhaust line, and

means for connecting a plurality of exhaust gas heaters with the flat side structure of said manifold casting adjacent the peripheral edge thereof.

5. 2. A manifold for connecting a plurality of exhaust gas heaters to the exhaust line of an internal combustion engine, having in combination, a large flat circular manifold casting provided with an intake in connection with the exhaust line and provided with

10 an outlet opening in the flat side adjacent the outer edge, and a nipple secured in said opening and arranged to be each connected to an exhaust gas heater and said nipple

15 extending into the interior of the flat manifold and provided each with a plurality of ports in its sides.

3. A manifold for connecting a plurality of exhaust gas heaters to the exhaust line

20 of an internal combustion engine, having in combination, a flat circular manifold casting provided with an intake in connection with the exhaust line and provided with a plurality of outlet ports in the flat side

25 structure adjacent the outer edge, nipples secured in said outlet ports and provided with inlet openings in registration with the interior of the manifold, and means for connecting a plurality of exhaust gas

30 heaters with the nipples to place the heaters in connection with the exhaust line.

4. A manifold for connecting a plurality of exhaust gas heaters to the exhaust line of an internal combustion engine, having in

35 combination, a manifold casting provided at its periphery with an intake in connection with the exhaust line, said manifold casting shaped substantially circular and flat, and means for connecting a plurality of

40 exhaust gas heaters with the flat side structure of said manifold casting adjacent the outer edge.

5. A manifold for connecting a plurality of exhaust gas heaters to the exhaust line

45 of an internal combustion engine, having in combination, a flat and circular manifold casting provided with an intake in connection with the exhaust line, said manifold casting shaped substantially circular for

imparting a swirling action to the exhaust 50 gases to spread the same about the interior of the manifold casting, and means for connecting a plurality of exhaust gas heaters with the flat side structure of said manifold casting near the periphery thereof, 55 thereby permitting an even distribution of the exhaust gases to all of said heaters.

6. A manifold for connecting a plurality of exhaust gas heaters to the exhaust line of an internal combustion engine, having 60

in combination, a manifold casting provided with an intake port in connection with the exhaust line, said manifold casting having two sides flattened and shaped substantially 65

circular in the plane of the flattened sides for spreading the gases and imparting a 70 swirling action thereto, the said casting provided with openings in the flattened side walls adjacent the outer edge, the openings

in the one side wall positioned directly opposite the openings in the other side wall, nipples extending through said openings and provided with openings registering with the interior of the manifold casting to permit

75 the exhaust gases to pass therein subsequent to the muffling operation, means for clamping said nipples to the casting, and means for securing an exhaust gas heater to each nipple.

7. A manifold for connecting an exhaust 80 gas heater to the exhaust line of an internal combustion engine, comprising a body portion having relatively large side walls connected at their edges by a relatively narrow

85 edge-wall to provide a chamber of flat formation, said body having an inlet for exhaust gases located in its edge wall, one of the side walls having an opening therein for

90 outlet of the exhaust gases, the said flat chamber having a thickness less than the diameter of the inlet, and a fixture adapted to be secured in said opening, said fixture being provided with a plurality of ports for the passage of the exhaust gases there-

95 through.

In testimony whereof I have affixed my signature.

CHARLES FORTH.
